UNITED STATES PATENT OFFICE.

TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

ELECTRIC SWITCH.

Application filed April 21, 1919. Serial No. 291,577.

To all whom it may concern:

Be it known that I, TONJES A. BOTH, a citizen of the United States, residing at Stratford, county of Fairfield, State of Connecticut, have invented an Improvement in Electric Switches, of which the following is a specification.

This invention relates to improvements in electric switches and has for its object the provision of means for causing an especially quick make and quick break of the switch parts. In most switches as heretofore constructed it was necessary to provide an expensive framework to keep the parts together and in accurate operative alignment and adjustment, and in others, it was necessary to depend too much upon the porcelain or other insulating body. This made it necessary to make the insulating body very accurately, which entailed the heavy cost of keeping the dies accurate to very close dimensions.

It is an object of my present invention to overcome these objections by providing a switch which depends largely upon the key shaft for limiting the movement of the parts and to retain them in proper alignment and adjustment.

A further object is to provide a switch wherein the movable contact serves as a bearing for some of the movable elements of the switch mechanism.

One physical embodiment of my invention is illustrated in the accompanying drawings, wherein:

Fig. 1 is a view of an ordinary socket containing switch means constructed according to my present invention.

Fig. 2 is a similar view showing the socket shell in vertical section.

Fig. 3 is a plan view of the switch removed from the socket shell.

Fig. 4 shows in perspective the parts of my improved switch in disassembled relation.

Fig. 5 is a cross sectional view on the line 5—5 of Fig. 3 looking in the direction of the arrows.

Fig. 6 is a view similar to Fig. 5, showing the parts in "circuit closed" position.

Fig. 7 is a view similar to Fig. 6 looking in the opposite direction.

Fig. 8 is a bottom view of the parts shown in Figs. 5, 6, and 7.

Fig. 9 is a view similar to Fig. 3, the top block and the movable parts having been removed.

Fig. 10 is a perspective view of the switch mechanism alone.

Figs. 11 to 14 are enlarged vertical medial sectional views of the movable parts of the switch shown in different positions of adjustment.

Referring to said drawings the numerals 20 and 21 indicate, respectively, the cap and body portion of a socket embodying my improved form of switch. 22 indicates any suitable key for operating the switch. The numerals 23 and 24 indicate, respectively, the top and bottom insulating blocks and 25 is the screw shell for receiving the base of an electric lamp or connecting plug. This shell is seated upon a portion of the shell connector 26 which lies alongside the insulating blocks and carries at its upper 70 end the binding screw 27 to which one of the wires is connected. The numeral 28 is applied to the center contact (see Figs. 4, 7 and 8), which is held in place by a rivet 29 which also serves to connect it with a connector 30, having a bent-up contact ear 31. Adjacent to ear 31 and extending in an opposite direction is a downwardly bent contact ear 33 of a connector 32 attached to the bottom insulating block by a screw 34 which also passes thru and holds in position a connector 35, thru which passes a binding screw 36 to which the other wire is connected.

It will be seen that in order to complete the circuit it will be necessary to provide means for bridging the space between contact ears 31 and 33, and for this purpose I have provided a U-shaped switch member, mounted for oscillation on a pin 37 received in suitable recesses in the lower insulating block, 38 and 39 designate contact fingers of switch member 37 for contacting with contact ears 31 and 33 respectively. Near its central portion the switch member is formed with an enlarged portion 40, having a preferably circular aperture 41, thru which passes a key shaft 42, carrying a key 22, and formed with a crank 43 which parts constitute the operating member of the switch. The numeral 44 designates a coil spring bearing against crank 43 and abutting at its other end against a U-shaped

- housing 45 between the arms of which crank 43 is located, and which is provided with bent over ear portions 46 forming shoes sliding in apertures 41.
- 5 The key shaft is journaled in a recess 47 in the lower insulating block and is held against endwise play by a slotted collar 48, fitting a reduced portion 49 on the shaft and receivable in a recess 50 in block 24.
- 10 It will be seen that when the key shaft is rotated housing 45 will be rotated in unison therewith, the shoes sliding in circular apertures 41. The pressure of spring 44 will therefore be exerted in a direction 15 which is alternately above and below pivot 37', and the switch member will be caused to alternately move upward and downward into and out of connection with contact ears 31 and 33, and this movement will take place 20 suddenly so that arcing at the contact points is reduced to a minimum.
- In Fig. 11 the key shaft is shown as being rotated in a clockwise direction, and the housing or operative member 45 and spring 25 44 are positioned in a line passing through pin 37'. Upon a slight further movement of the key shaft the switch member will be violently thrown downward for closing the circuit. Fig. 12 shows the parts in a 30 position for closing the circuit by rotating the shaft in the opposite direction. Figs. 13 and 14 show the switch member in closed circuit position; the parts being shown in position just before the switch 35 member is to move upward for breaking the circuit.
- It will be seen that during a complete rotation of the key shaft in one direction the switch member will be moved through 40 two strokes or one complete oscillation. If rotated in the reverse direction two strokes of the switch member will again result, but as these strokes do not occur at the same point in the rotation of the shaft the mechanism 45 possesses four points of action—two in either direction of rotation.
- It will be noted also that the key shaft serves as a stop to limit the movement in both directions of the switch member and 50 that the switch member provides a bearing for the yieldable operative means for actuating said switch member.
- It will be seen therefore that I have provided a device which fulfills the objects 55 primarily stated and while I have shown a single embodiment of my invention, it is clear that other forms thereof may readily be provided without departing from my invention as defined in the following claims:—
- 60 1. In an electric switch, a pivoted switch member provided with a transverse opening in the body thereof, an operating member extending through said opening and provided with a crank, a movable member 65 having a shoe extending into the opening

providing sliding engagement with the walls of the switch member about said opening, and a spring bearing at one end in said movable member and the other end against said crank.

2. In an electric switch, a pivoted switch member comprising spaced arms having transverse openings therein, a key-shaft extending through said openings and provided with a crank between said arms, a movable member between said arms and having shoes extending into the openings providing sliding engagement with said switch member and adapted to slide circumferentially in the openings, and a spring connecting the movable member and the crank.

3. In an electric switch, a pivoted switch member having spaced contact arms provided with transverse openings, a key shaft extending through said openings provided with a crank, a substantially U-shaped housing between said arms and extending on opposite sides of said crank, said housing being provided with outwardly extending shoes projecting into the openings having sliding engagement with the switch member and adapted to slide circumferentially in the openings, and a compression spring within the housing bearing at one end against the housing and at the other end against said crank.

4. In an electric switch, a pivoted switch member having spaced contact arms provided with transverse openings, an operating shaft extending through said openings and provided with a crank, a housing between said arms having spaced sides on opposite sides of the crank and guiding elements having sliding engagement with said arms in said openings, and a spring carried by said housing between said sides and extending between the same and said crank.

5. In an electric switch, a pivoted switch member having spaced contact arms provided with transverse openings, an operating shaft extending through said openings and provided with a crank between the arms, a housing having spaced sides on opposite sides of the crank and guiding elements having sliding engagement with the walls of said openings, and a spring within the housing and bearing at one end against one end of the housing and at the other end against the crank.

6. An electric switch comprising a support, a crank shaft, a crank connected therewith, a switch member, a pivot therefor at one end, said switch member having contact fingers at the other end and an enlarged portion intermediate the ends having an aperture surrounding said crank shaft, a housing carried by said switch member, a spring member bearing at one end on said housing and at its other end upon said crank, means

on said housing connecting it to said enlarged portion and providing a loose connection between said crank and said switch member, and means for moving said crank shaft to shift the switch member.

7. An electric switch comprising a support, a crank shaft, a crank connected therewith, a pivoted switch member having a switch finger thereon and an enlarged apertured portion intermediate its ends surrounding said crank shaft, a housing having ears carried by said switch member and forming shoes for sliding upon said switch member, a spring interposed between the 10 crank and the housing and communicating the driving movement of said crank to said housing and said shoes so that said shoes can be moved entirely around the aperture in said switch member upon a complete rotation of the crank shaft, and thereby placing the switch finger, the crank, crank shaft, and pivot in alinement at several different points in the travel of the crank, at which points the switch shall be moved.

8. An electric switch, comprising a manually operative rotatable member having a curved guiding wall, a pivoted switch member, a member slidable on said guiding wall on said switch member, and a spring member 25 connected to the slidable member and connected to said manually operative member, said manually operative member, said spring member and said slidable member being arranged to turn together during most of the 30 rotation of the manually operative member.

9. An electric switch comprising a support, a crank, a pivoted switch member, contacts adapted to be joined thereby, said switch member having an apertured portion thereon, a housing carried by said switch member and having a bearing member sliding on the walls forming the periphery of said aperture, and a spring enclosed by the housing connecting said housing and said 40 crank to position the housing in correspondence with the crank.

10. An electric switch comprising a support, an operative member, a switch member, a pivot therefor, said switch member 45 having an opening through which the operative member passes, said operative member and said opening forming means for limit-

ing the movement of said switch, said operative member also constituting means for preventing transverse movement of the switch and maintaining its alinement, said pivot and said operative member being the sole means for limiting the movement of the parts and for retaining them in proper alinement and adjustment.

11. An electric switch comprising a pivoted switch member, having an enlarged portion with an opening, an operating member passing therethrough, a housing extending on opposite sides of the operative member and having portions sliding on the switch member in said opening, a spring enclosed by the housing and connecting said operative member and said housing, said operative member being rotatable upon its axis and adapted for 60 moving the housing and the spring around said axis.

12. An electric switch comprising a pivoted switch member, a key shaft, said switch member being provided with an opening intermediate the ends thereof, connecting means extending between the key shaft and the switch member and having sliding contact with the walls of the opening so that it will slide about the periphery of the opening 70 under the action of the key shaft.

13. An electric switch comprising a switch member having an opening therein, a key shaft passing through said opening, connecting means joining the key shaft to said switch member at the opening, said connecting means having sliding connection with said switch member in said opening and adapted to slide around the periphery of said opening under the influence of the key shaft.

14. An electric switch comprising a switch member, an opening therein, a pivot for said switch member, a key shaft, a crank thereon, a housing, a spring therein, a shoe on said housing passing through the opening in the switch member and engaging the switch member between the portions thereof and means on said housing engaging the crank and retaining the spring against the crank pin, said crank moving said housing around 90 the opening in the switch member.

In testimony whereof I affix my signature.

TONJES A. BOTH.
